UNITED STATES PATENT OFFICE.

EDWARD JAMES HENDERSON, OF HAMILTON, ONTARIO, CANADA, ASSIGNOR TO THE
P. B. YATES MACHINE COMPANY, LIMITED, OF HAMILTON, ONTARIO, CANADA.

NAILING MACHINE.

Application filed July 10, 1922. Serial No. 573,822.

To all whom it may concern:

Be it known that I, EDWARD JAMES HENDERSON, a subject of the King of Great Britain, and a resident of the city of Hamilton, 5 in the county of Wentworth, Province of Ontario, Dominion of Canada, have invented certain new and useful Improvements in Nailing Machines, of which the following is a specification.

10 My invention relates to improvements in nailing machines with particular reference to machines for nailing boxes and the object of the invention is to improve the construction of such machines whereby the output 15 thereof may be increased.

My invention consists essentially in the application to a nailing machine having nail driving means and a work supporting table supported in spaced relation therebelow, of means for varying the effective distance between the work support and the nail driving means automatically with the operation of the nail driving means, provision being made for any desired number of 20 adjusted positions and provision also being made for causing the various adjusted positions to occur in accordance with a previously arranged sequence, all as hereinafter more particularly described and illustrated 25 in the accompanying drawings in which;

Fig. 1 is a front elevation of a portion of a nailing machine showing my invention applied thereto, the work supporting table of the machine being in section.

Fig. 2 is a side elevation of a portion of a nailing machine showing the application of my invention thereto, a portion being broken away and taken in section on the line 2, 2 of Figs. 1 and 3.

Fig. 3 is a top plan view of the work supporting table.

Fig. 4 is a diagrammatic view showing the position of a pair of adjusting blocks and a box supported thereby during the operation of nailing the first side on a box.

Fig. 5 is a similar view showing the position during the second operation, that of nailing the bottom on the box.

Fig. 6 is a similar view showing the position during the third operation, that of nailing the second side on the box.

In the drawings like characters of refer-

ence indicate corresponding parts in the different views.

1 is the main frame of a nailing machine 55 which has the work supporting table 2 secured thereto after the usual manner as for instance by bolts 3.

4 indicate nail holding chucks which are rigidly supported after the usual manner 60 from the main frame 1 in brackets 5.

These chucks are arranged in two sets, which sets are disposed in spaced relation transversely of the machine, one set being at the left and the other at the right and all 65 chucks being at the same level.

Nails are fed, after the usual manner, from a reservoir (not shown) to the chucks 4 through tubes 6, but as this nail feeding mechanism forms no part of my present invention it will not be described in detail.

7 are nail driver rods which are associated with the chucks 4 in the well known manner, used in this type of machine.

8 (see Fig. 2) is a reciprocatory head 75 which is movable up and down on vertical guides formed on the main frame 1.

9 are forwardly disposed heads rigidly carried by the head 8 and operatively engage the upper ends of the nail driver rods. 80

The reciprocatory head 8 may be operated from the main drive of the machine in any suitable manner such as by the crank 10 and connecting rod 11 (see Fig. 1) but as this follows well known practice in nailing 85 machines and does not form part of my present invention detailed description is not thought necessary.

12 are stepped adjusting blocks extending forwardly and rearwardly of the machine and are slidably supported upon the upper face of the work table 2.

In the form shown the blocks are provided with two steps "A" and "B" (see Fig. 1).

13 are slides to which the blocks 12 are rigidly secured, said slides being freely mounted in guide slots 14 formed in the table 2.

The slides 13 extend below the under face 100 of the table 2, and 15 are rollers mounted on depending studs 16 which studs are secured to the slides 13.

17 are tension coil springs secured to the

inner ends of the slides 13 and to the under face of the table by a bolt 18.

These tension springs therefore tend to draw the slides 13 inwardly towards the center of the table.

20 is a shaft rotatably journalled in bearings 21 carried by the under side of the table 2 and extends transversely of the table.

22 is a ratchet wheel having the three ratchet teeth 23 and is rigidly secured to one end of the shaft 20.

24 is a hand wheel rigidly secured to the other end of the shaft 20.

25 are cam wheels rigidly secured upon the shaft 20 and each is provided with the cam surface 26 on its outer side.

The rollers 15 are held in engagement with the cam surfaces 26 by means of the tension springs 17.

27 are rigid portions of a work gripping device and are rigidly secured upon the main frame 1.

28 are movable portions of this work gripping device and are slidale in and out transversely of the machine.

The gripping device is normally maintained in the open position by the springs 29 which force the movable sections 28 outwardly.

30 is a shaft journalled transversely of the main frame 1 and carries the inwardly disposed cam members 31 adjacent to each end thereof, the cam surfaces of which engage rollers 32 supported in brackets 33 which brackets are connected to the movable portions 28.

34 is a bell crank lever rigidly carried by the shaft 30.

35 is a connecting rod having one end connected to the reciprocatory head 8 at 36 and the other end to one arm of the bell crank 34 at 37.

38 is a second connecting rod having one end secured to the other arm of the bell crank at 39 and carrying at its lower end a bracket 40 which is journalled upon the shaft 20.

Within this bracket 40 is mounted a pawl 41 which engages the ratchet teeth 23.

42 is a turnbuckle within the connecting rod 38.

43 are the end members of a wooden box. 44 are the side members and 45 is the bottom member of the box.

46 is a band brake secured to the under side of the table 2 and operatively engages the periphery of one of the cam wheels 25.

The construction and operation of my invention is as follows;

60 The operation of nailing a box consists in first nailing the first side onto the end members (see Fig. 4), then the bottom member is nailed on (see Fig. 5), and finally the second side (see Fig. 6).

65 In these operations it will be apparent

that the height of the work varies during the different operations and since it is essential that the top of the work be supported in proper relation below the chucks 4, some means of taking care of the difference in heights must be provided and it is with a view of accomplishing this result that I have devised my invention.

Hitherto this has been accomplished in various ways such as by providing for adjustments up and down of the work table 2 or of a supplementary table carried by the main table, but this has been cumbersome and has been accomplished manually when desired by the operator.

In the form of my invention illustrated the first operation in constructing a box consists in nailing on the first side (see Fig. 4).

In this operation the adjusting blocks 12 are stationed so that the steps "B" are below the chucks 4, the height of the step "B" being equal to the thickness of one of the side pieces 44.

The end pieces 43 are slipped into the open grips 27 and 28 and rest upon the steps "B". The side 44 is then placed above the ends in position under the chucks 4 and the nail driving mechanism is operated in the usual manner by releasing a trip (not shown) which causes the reciprocatory head 8 to descend thus operating the nail driver rods 7 after the usual manner.

The next operation consists in nailing on the bottom 45 and since the height of the box in this case is less than the width it is necessary to compensate for this difference, and in nailing the bottom the adjusting blocks 12 move inwardly so that the steps "A" are under the chucks and support the ends 43 (see Fig. 5).

This inward movement of the blocks 12 is accomplished as follows.

During the previous descent of the reciprocatory head 8 in nailing the first side 44, as above described, through the medium of the connecting rod 35, bell crank 34 and connecting rod 38 the pawl 41 was moved anti-clockwise (see Fig. 2) and slipped freely around the ratchet wheel 22 to grip the next tooth 23 thereon.

During the following ascent of the head 8 the pawl 41 rotated the ratchet wheel 22 and with it the shaft 20 through 120 degrees and thus the cam wheels 25 were rotated through one-third of a revolution. This brought the lowest portion "D" of the cam surfaces 26 in contact with the rollers 15 so that the blocks 12 were drawn inwardly to their full extent by the springs 17.

The bottom 45 is now nailed similarly to the side 44 above described and during this reciprocation of the head 8 the ratchet wheel 22 is again rotated through 120 degrees with a consequent rotation of the cam

wheels 25 through a second third of a revolution, bringing the high points "E" of the cam surfaces 26 into engagement with the rollers 15 so that the slides 13 and with them 5 the blocks 12 are moved outwardly to their full extent and the blocks 12 are removed entirely from under the chucks 4.

This is the position for nailing the second side (see Fig. 6).

10 During the nailing of this second side the ratchet wheel 22 and cams 25 are again rotated through the last third of the revolution bringing them back to the original position in which the steps "B" are again under 15 the chucks 4 and the apparatus is ready for commencing to nail another box.

The band brake 46 which engages the periphery of one of the cam wheels 25 serves to prevent the cams from over 20 rotation during the operation of the machine.

It will be noted from an examination of Figs. 4, 5 and 6 that the height of the bottom of the chucks 4, above the table 2, (indicated by the letter "C" in Figs. 4, 5 and 6) 25 is constant and it is essential that, in the different nailing operations, if the height of the work is less than this distance "C", a filler of the proper height must be placed beneath the work so that the height of the 30 work plus the height of the filler is equal to the height "C".

This is accomplished in my invention automatically with the operation of the machine and when once set the operator has 35 simply to go through the operations of inserting the material without paying any heed whatever to this adjustment for height.

It will be apparent that the stepped adjusting blocks "B" are moved in and out automatically with the operation of the nail driving mechanism and that by the ratchet device and the cam wheels 25, the movement of these blocks is such that the various steps 40 may be brought into operative position under the chucks 4, in accordance with any pre-arranged sequence.

During each descent of the reciprocating head 8 and the consequent operation of the nail driving mechanism the inwardly directed cam members 31 force the movable grip members 28 inwardly so that the work 50 is firmly gripped during the nail driving operation.

This gripping arrangement is also operated automatically with the operation of the nailing mechanism.

Various modifications may be made in my invention without departing from the spirit of the invention or the scope of the claims 55 and therefore the exact forms shown are to be taken as illustrative only and not in a limiting sense.

For instance while I have described a specific embodiment of my invention with 60 reference to a case in which only three dif-

ferent heights are used it is obvious that it may equally well be applied to cases where any number of adjustments are necessary, it being only necessary that the number of teeth on the ratchet 22 correspond to the 70 number of adjustments desired and that the cam surfaces 26 be properly constructed.

Also the brake 46 may not be mounted to engage one of the cam wheels but might engage a separate brake drum carried by the 75 shaft 20.

What I claim as my invention is:

1. In a nailing machine the combination with nail driving means and a work supporting table situated in spaced relation 80 therebelow, of a stepped block slidably carried on the upper face of the work supporting table, said block constituting a work support below the nail driving means, and means for moving the stepped block upon the table whereby any of the various steps thereof may be stationed below the nail driving means.

2. In a nailing machine the combination with nail driving means and a work supporting table situated in spaced relation 90 therebelow, of a stepped block slidably carried on the upper face of the work supporting table, said block constituting a work support below the nail driving means, means 95 operatively connecting the nail driving means with the stepped block whereby the latter is automatically moved upon the table by the former and the various steps of the block are positioned below the nail driving 100 means in accordance with a definite prearranged sequence.

3. In a nailing machine the combination with nail driving means and a work supporting table situated in spaced relation 105 therebelow, of a stepped block slidably carried on the upper face of the work supporting table, said block constituting a work support below the nail driving means, spring means forcing the block in one direction, a cam associated with the block for moving it in the reverse direction against the action of the aforesaid spring, and means operatively connecting the nail driving means and cam whereby the latter is 110 automatically rotated from the former and the various steps of the block are positioned successively below the nail driving means.

4. In a nailing machine the combination with nail driving means and a work supporting table situated in spaced relation 120 therebelow, of a stepped block slidably carried on the upper face of the work supporting table, said block constituting a work support below the nail driving means, spring means forcing the block transversely of the table in one direction, a shaft rotatably supported from the under side of the table and extending transversely thereof, a ratchet wheel at the outer end of said 125

shaft, a connecting rod having a pawl at one end operatively engaging the ratchet and being connected at the other end to the nail driving means, and a cam on the transverse 5 shaft operatively associated with the stepped block for forcing it transversely of the table against the action of the aforesaid spring.

5. In a nailing machine the combination with the main frame of the machine, nail 10 holding chuck rigidly carried thereby, a work supporting table supported by the main frame in spaced relation below the chucks, nail driving means associated with the chucks and a reciprocating head 15 mounted upon vertical guides on the main frame and operatively engaging the nail driving means, of a stepped block slidably supported upon the upper face of the table, and means operatively connecting the 20 stepped block with the reciprocating head, whereby the block is moved transversely upon the table automatically with the reciprocation of the head and whereby successive reciprocations of the head position the 25 various steps of the block successively below the chucks in accordance with a prearranged sequence.

6. In a nailing machine the combination with the main frame of the machine, nail 30 holding chucks rigidly carried thereby, a work supporting table supported by the main frame in spaced relation below the chucks, nail driving means associated with the chucks and a reciprocating head mounted 35 upon vertical guides on the main frame and operatively engaging the nail driving means, of a stepped block freely supported upon the upper face of the table, a slide mounted in a transverse guide slot in the 40 table, said block secured to said slide, a roller carried by the under face of the slide, a shaft rotatably carried at the under side of the table and extending transversely thereof, a cam rigidly carried by said shaft 45 and engaging the aforesaid roller, a ratchet wheel rigidly carried by the outer end of the shaft, a bell crank lever pivotally mounted upon the main frame, a connecting rod connecting one arm of the bell crank to the 50 reciprocating head, a second connecting rod having one end connected to the other arm of the bell crank and carrying a pawl at its other end, said pawl operatively engaging the aforesaid ratchet wheel, said cam adapted 55 to move the slide and stepped block in one direction transversely of the table, and spring means resisting such movement.

7. In a nailing machine the combination with the main frame of the machine, a plurality 60 of sets of nail holding chucks, rigidly supported by the main frame, the sets spaced transversely of the machine, a work supporting table rigidly carried by the main frame in spaced relation below the chucks, nail 65 driving means associated with the chucks, nail driving means associated with the chucks,

and a reciprocating head mounted upon vertical guides on the main frame and operatively engaging the nail driving means, of a plurality of stepped blocks slidably supported upon the upper face of the table, 70 each block constituting a work support below one set of chucks, and means for moving the blocks transversely upon the table whereby by the various steps thereof may be positioned below the sets of chucks. 75

8. In a nailing machine the combination with the main frame of the machine, a plurality of sets of nail holding chucks, rigidly supported by the main frame, the sets spaced transversely of the machine, a work 80 supporting table rigidly carried by the main frame in spaced relation below the chucks, nail driving means associated with the chucks, and a reciprocating head mounted upon vertical guides on the main frame and operatively engaging the nail driving means, of a plurality of stepped blocks slidably supported upon the upper face of the table, 85 each block constituting a work support below one set of chucks, and means for simultaneously moving the blocks transversely upon the table whereby corresponding steps 90 thereof may be positioned below the various sets of chucks.

9. In a nailing machine the combination 95 with the main frame of the machine, a plurality of sets of nail holding chucks, rigidly supported by the main frame, the sets spaced transversely of the machine, a work supporting table rigidly carried by the main frame in spaced relation below the chucks, nail driving means associated with the chucks, and a reciprocating head mounted upon vertical guides on the main frame and operatively engaging the nail driving means, 100 of a plurality of stepped blocks slidably supported upon the upper face of the table, each block constituting a work support below one set of chucks, means for simultaneously moving the blocks transversely upon 105 the table whereby corresponding steps thereof may be positioned below the various sets of chucks and means operatively connecting said block moving means with the reciprocating head whereby the latter is actuated by 110 the former. 115

10. In a nailing machine the combination with the main frame of the machine, two sets of nail holding chucks rigidly supported by the main frame, the sets spaced transversely of the machine, a work supporting table rigidly carried by the main frame in spaced relation below the chucks, nail driving means associated with the chucks, and a reciprocating head mounted upon vertical 120 guides on the main frame and operatively engaging the nail driving means, of two stepped blocks slidably supported upon the upper face of the table, each block constituting a work support below one set of 125 130

chucks, a slide secured to the under face of each block, said slides freely mounted in aligned transverse slots in the table, a roller carried by the under face of each slide, a shaft rotatably supported at the under face of the table and extending transversely thereof, a pair of outwardly disposed cam wheels rigidly carried by the shafts, spring means forcing the slides inwardly and maintaining the aforesaid rollers in engagement with the cam surfaces of the cam wheels, and means operatively connecting the transverse shaft and the reciprocatory head whereby the latter is rotated by the reciprocation of the former.

11. In a nailing machine the combination with the main frame of the machine, two sets of nail holding chucks rigidly supported by the main frame, the sets spaced transversely of the machine, a work supporting table rigidly carried by the main frame in spaced relation below the chucks, nail driving means associated with the chucks, and a reciprocatory head mounted upon vertical guides in the main frame and operatively engaging the nail driving means, of two stepped blocks slidably supported upon the

upper face of the table, each block constituting a work support below one set of chucks, a slide secured to the under face of each block, said slides freely mounted in aligned transverse slots in the table, a roller carried by the under face of each slide, a shaft rotatably supported at the under face of the table and extending transversely thereof, a pair of outwardly disposed cam wheels rigidly carried by the shafts, spring means forcing the slides inwardly and maintaining the aforesaid rollers in engagement with the cam surfaces of the cam wheels, a ratchet wheel rigidly carried by one end of the transverse shaft, a bell crank lever pivotally mounted upon the main frame, a connecting rod connecting one arm of the bell crank to the reciprocatory head, and a second connecting rod having one end connected to the other arm of the bell crank, said second connecting rod carrying a pawl at its other end, said pawl operatively engaging the aforesaid ratchet wheel.

EDWARD JAMES HENDERSON.
